MAT FOR PLAYING HOPSCOTCH

Philip C. Gould, Marion, Conn.

Application April 14, 1954, Serial No. 29,993

Term of patent 14 years

(Cl. D34—5)

To all whom it may concern:

Be it known that I, Philip C. Gould, a citizen of the United States, residing in Marion, county of Hartford, and State of Connecticut, have invented a new, original, and ornamental Design for a Mat for Playing Hopscotch, of which the following is a specification, reference being had to the accompanying drawing, forming part thereof.

The figure is a top plan view of a mat for playing hopscotch, showing my new design.

The mat is of conventional thickness.

I claim:

The ornamental design for a mat for playing hopscotch, as shown and described.
